ATTORNEY.

UNITED STATES PATENT OFFICE.

EDWARD W. SHANNON, OF WATERBURY, CONNECTICUT.

DESIGN FOR A SPOON.

SPECIFICATION forming part of Design No. 20,809, dated June 2, 1891.

Application filed May 7, 1891. Serial No. 391,952. Term of patent 7 years.

To all whom it may concern:

Be it known that I, EDWARD W. SHANNON, a citizen of the United States, residing at Waterbury, in the county of New Haven and State of Connecticut, have invented certain new and useful Improvements in an Original Design for a Spoon, of which the following is a full, clear, and exact specification.

In the drawings which are hereunto annexed, Figure 1 shows in perspective a spoon whose bowl is conformed in accordance with my design. Fig. 2 shows the same spoon in plan view.

From the handle, which I denote by the numeral 1, spring two divergent and curved lines 2, whose outer ends turn downward and inward, as shown at 3. From the end of these curved lines curves 4 extend outward. The combinations of the lines 2 and 4 upon either side of the handle form doubly-curved notched shoulders at the upper end of the spoon-bowl.

From the termination of the short curves 4 the sides of the bowl for about half the length of the latter are curved only very slightly, so as to give to the bowl the appearance of being of nearly uniform width as to its upper half. Below the point 5 the side lines of the bowl converge, as shown at 6, in curved lines, and terminate in a point 7, which is slightly flattened and whose outer curve is of short radius and is struck from the median line of the bowl near its lower end.

I claim—

The design for a spoon, substantially as herein shown and described.

In testimony whereof I affix my signature in presence of two witnesses.

EDWARD W. SHANNON.
